Attorney.

UNITED STATES PATENT OFFICE.

HAROLD M. GUSDORF, OF INDIANAPOLIS, INDIANA.

POWER TRANSMISSION.

Application filed May 25, 1921. Serial No. 472,574.

To all whom it may concern:

Be it known that I, HAROLD M. GUSDORF, a citizen of the United States, residing at Indianapolis, in the county of Marion and 5 State of Indiana, have invented new and useful Improvements in Power Transmission, of which the following is a specification.

The object of this invention is to provide 10 a pulley-belt for the transmission of power, which will have a single line of pull of substantially inelastic material on that side which is the most remote from a pulley around which the belt operates. This is to 15 avoid that stretching and consequent loosening of the belt which reduces its efficiency, and, as supplementing this quality in the belt, the further object of my invention is to provide a less firm opposite side, also pitted 20 with cup-like depressions that will give a vacuum-grip against the face of the pulley and provide room in the cups for the material of the inner curve of the belt, which is compacted in passing around the pulley, 25 thereby avoiding strain on the firm outer belt surface.

A further object is to utilize hog-skin leather, tanned to preserve the desired inelastic grain surface and cup formations 30 natural to it, and to join the leather strips together in a manner to produce a belt of the required length and of uniform strength and efficiency.

I accomplish the above, and other objects 35 which will be disclosed hereinafter, by the means illustrated more or less diagrammatically in the accompanying drawings, in which—

Fig. 1 is a longitudinal vertical section of 40 two pieces of hog-skin leather, magnified, showing the manner in which the adjacent ends to be joined are cut on a bevel and the resulting thin edges removed. Fig. 2, is a similar view in sections on the line 2—2 of 45 Fig. 3, showing the beveled ends cemented together to form a continuous belt. Fig. 3, is an underside view of a portion of my improved belt formed of two joined pieces. Fig. 4, shows two pulleys connected by my 50 improved belt, and Fig. 5 is a cross section of hog-skin leather greatly magnified to show interwoven fibres imparting a firm surface to the leather on the grain side, and

showing the cup-like indentations of the opposite side. 55

Like reference numerals indicate like parts in the several views of the drawings.

The outer firm belt surface is represented by the heavy line 6, in the drawings, and the cup-like indentations are shown at 7. 60 The latter provide the spaces for the displacement of the belt material on the side next to the pulley in the bending of the belt around the pulley; and the exhaustion of air in them caused by this partial closure toward each other of the walls of the cups produces a partial vacuum that adds to the pull of the belt on the pulley. This inner belt surface, pitted with cups 7, is sufficiently 65 elastic to secure the required change in surface area on that side to fit the belt to the curvature of the pulley without straining the outer side of the belt, and a line of pull on the outer side of the belt of unvarying length is obtained, which adds materially to 70 the life and efficiency of the belt. 75

It is necessary in practice to join the ends of a straight strip together into a continuous belt, and often, and particularly where hog-skin leather is the source of supply for such strips, to connect a plurality of shorter lengths into longer ones; and this requires a certain treatment of the ends to secure a strong joint. The ends to be joined are cut obliquely on the bevels *a* and *b*, and a thin 80 edge *c* on the inner and less firm side is removed to get rid of this very weak material so the joint will be of the stronger portions. It is also desirable, in most cases, to remove the sharp end shown by the dotted lines *d*, 85 of the firm side of the belt for the reason that this end is more apt to become loose and start a rupture of the joint if left on. The difficulty is overcome by the removal in the manner shown, thereby forming a reverse bevel which, when the ends are cemented together and the joints pressed in the usual manner, makes a practically smooth and more satisfactory job. 90

It is known that there is a difference in 100 density between the ham-and shoulder-ends of the hog-skin, the ham end being the firmer, which, in one-ply belts, requires that as much of the dense side of the shoulder-ends be left as possible, and the cut made on 105 the firm side of the ham-end, as shown in

Figs. 1 and 2. Thereby, the ham-end is lapped by the shoulder-end and a stronger joint is secured than if the ends were reversely beveled.

5 While I have here illustrated and mentioned hog-skin leather as a natural product when suitably treated in tanning, a belt material having the same essential characteristics may be produced entirely by artificial 10 means, and I therefore do not desire to limit

my invention to hog-skin or any certain material more than is required by the appended claim.

I claim:—

A hog-skin belt having the flesh side next 15 the pulley and the grain side out.

Signed at Indianapolis, Indiana, this the 23rd day of May 1921.

HAROLD M. GUSDORF.
